STOVE

Oscar Kriner, Martinsville, Ind.

Application June 17, 1941, Serial No. 398,473

5 Claims. (Cl. 126—73)

This invention relates to stoves, and has for one of its objects the production of a simple and efficient flue for stoves and the like, which is built from a plurality of blocks so constructed and arranged as to provide an efficient draft so that the gases and flame may have a free passage at all times through to the combustion chamber of the stove.

A further object of this invention is the production of a simple and efficient block construction which may be assembled with other similar blocks to provide an efficient stove flue having a plurality of draft openings which are arranged in a manner to be shielded to prevent the openings from being clogged.

Another object of this invention is the production of a cast base which supports the flue in such a manner as to provide an "under the flue draft."

Other objects and advantages of the present invention will appear throughout the following specification and claims.

In the drawings:

Figure 1 is a vertical sectional view of a stove, certain parts being shown in elevation and showing the improved flue assembly;

Figure 2 is a horizontal sectional view taken on line 2—2 of Figure 1;

Figure 3 is a horizontal sectional view taken on line 3—3 of Figure 1;

Figure 4 is a horizontal sectional view taken on line 4—4 of Figure 1;

Figure 5 is a vertical sectional view taken on line 5—5 of Figure 2;

Figure 6 is a fragmentary perspective view of a series of flue blocks and a portion of a stove casing, such as the drum and lining, and showing the outer faces of the blocks;

Figure 7 is a fragmentary perspective view of a series of flue blocks and a portion of a stove casing such as the drum and lining and showing the inner face of the flue blocks;

Figure 8 is a perspective view of one of the flue block supporting castings;

Figure 9 is an enlarged fragmentary vertical section through a series of flue blocks and showing a part of the stove casing.

By referring to the drawings, it will be seen that 10 designates the stove which is provided with the conventional drum 11 and a lining 12. A grate 13 is supported within the stove on the ring 13^a of the conventional type. The ring 13^a is supported by the bolts 14^a which secure the legs 15^a to the stove.

In carrying out my invention, I preferably pro-

vide a plurality of cast base blocks or segments 14 which rest upon the ring 13^a, and fit close against the lower portion of the drum 11, as shown in Figures 1 and 3. These base blocks 14 or segments 14 constitute a support for the flue blocks hereinafter described. Each block 14 is curved to fit snugly against the inner face of the drum 11, and is provided at each end with a vertically extending inwardly tapering rib 15, as shown in detail in Figure 8, and also illustrated in Figure 3. The lower end of each rib 15 is notched, as at 16, near its inner face so as to fit snugly over the ledge portion 17 of the ring 13^a—note Figure 1. In this manner the base blocks 14 or segments which constitute segmental blocks 14 will be firmly anchored in position and the respective ends of the blocks 14 fit snugly against the usual fire clay brick to form a circular unit to protect the lower portion of the drum 11, as will be obvious by considering Figure 1.

Within the stove 10, and arranged at opposite sides between the conventional stove lining A, I provide a special flue lining which comprises a plurality of flue blocks 18 arranged in a series 25 one above the other, as indicated in Figure 1, to a desired height within the stove 10, and the lower block resting upon the upper edge of the segmental block 14 above described, each block 18 comprising a straight-walled body having a straight vertical outer wall 19 and a transversely straight inner wall 20, which wall 20 is inclined from the lower edge of the block upwardly toward the front wall of the block. The upper and lower ends of the blocks 18 are flat so that the lower edge of one block 18 may rest upon the flat upper edge of the lower block, as shown in Figures 1, 6, 7 and 9. The vertical side edges 21 are inclined from the outer toward the inner wall so as to permit the inclined side edges of the adjoining blocks to snugly fit against the lining or fire clay brick A. The lower faces of the lower blocks 18 rest upon the upper faces 22 of the ribs 15 of the segmental blocks 14, and these blocks 18 span the curved portions of the blocks 14, thereby providing "under the flue draft" through the ports 23 formed by the differences in shape of the blocks 18 and the blocks 14. Blocks 18, by spanning the upper edges of the blocks 14 will provide this efficient "under the flue draft."

Each block 18 is provided with an inwardly inclined notch 24, and the notches 24 in the lower blocks register with the ports 23 above described, thereby enlarging the area adjacent the ports 23 and directing the draft upwardly between the

lining 12 of the stove and the outer faces 19 of the blocks 18. These inclined notches 24 are inclined from a point inset from the inner faces and from the bottom edges of the blocks and upwardly toward the outer faces of the blocks. Each block 18 is also provided with an inclined notch 25 at its upper end and the inclined notches 25 are inclined from the inner faces 20 of the blocks from a point below the upper edges of the blocks upwardly to points inset from the outer faces 19 of the blocks. Consequently, when one block is set upon the upper edge of a lower block in the manner as shown in the drawings, the upper blocks 18 being placed directly above the lower block 18, as shown in Figures 6 and 7. The upper notches 25 in the lower blocks will register with the lower notches 24 or upper blocks, thereby providing an upwardly inclined flue passage between the blocks and through the adjoining upper and lower faces of the blocks. Since the blocks 18 are straight, a vertical flue passage 26 is provided upon each side of the stove adjacent the outer face throughout the entire height of the flue blocks. Furthermore, by having the notches 24 extending at an incline from the lower edges of the blocks upwardly toward the outer faces of the blocks, the inner edges 27 of the blocks will constitute a shield to prevent the flue openings extending between the blocks from becoming clogged since the fuel will naturally form across the flue openings between the blocks in the manner as shown in Figure 9, thereby permitting gases and fumes to pass up through the flue openings formed by the notches 24 and 25 in the direction of the arrows indicated in Figure 9.

From the foregoing description it will be seen that a very simple and efficient means has been provided for building-up a flue upon opposite sides of a stove or other heating apparatus involving a plurality of super-imposed specially constructed blocks resting upon segmental base blocks wherein the super-imposed flue blocks are provided with straight outer faces which span the base blocks to provide an "under the flue draft," and wherein various flue blocks are mounted one upon the other and are provided with registering upwardly inclined notches to provide an upwardly inclined draft from the combustion chamber up through the flue channels 26. By means of the specially constructed blocks which have been illustrated and described, a very simple and efficient means is provided wherein the flue of the stove may be renewed or replaced should occasion arise, and wherein the flue may be easily built-up to properly protect the metal portions of the stove and at the same time provide an efficient draft, avoiding gases and fumes and facilitating the burning of the fuel, thereby operating in a most economical manner.

It should be understood that the blocks 14 may be made of any metal such as is ordinarily provided in castings of this character, but the flue blocks are preferably formed of fire brick or other suitable material which will be fire-resistant. These flue blocks may be made of clay or as stated above of any heat-resistant material and the flues may be constructed to any suitable height by adding one or more layers of flue blocks. Furthermore, the flue blocks may be made of any suitable width to be accommodated in any particular style of stove, and the flues are self-cleaning and will not become clogged because of the formation of the notches 24 and 25 which are inclined upwardly toward the flue passages 26 and

downwardly toward the combustion chamber. Because of the structure illustrated and described explosions of confined gas in the stove will be avoided due to the efficient draft and the various outlets provided for the escape of gas out through the flue passages. All gas and soot is burned in the combustion chamber at the same time the coal is being burned. By having the open spaces under the flue due to the shape of the segmental blocks 14 next to the burning coal, the flame may pass up the flue at once when refilling the stove. This is possible due to the fact that the flue blocks which are straight span the curved or segmental block castings 14 as above described. These blocks 14 because of their shape will protect the outside drum or barrel of the stove from burning out. As clearly illustrated the flue blocks are so shaped that when they are assembled a plurality of pockets are provided at the draft holes or slots around the entire area of the flue and because of the manner in which these slots are protected as above described, these slots will not become clogged and are self-cleaning because of the fact that they incline downwardly toward the combustion chamber while at the same time gas and flame may have a free passage upwardly through the combustion chamber.

It should be understood that detail changes in the construction may be employed without departing from the spirit of the invention, so long as such changes fall within the scope of the appended claims.

Having described the invention, what is claimed as new is:

1. In combination with a stove, a grate and supporting ring, a flue supporting means carried by the ring and comprising a plurality of segmental blocks, each segmental block being outwardly curved and having vertically extending inwardly projecting tapering ribs, each block having vertical side edges inwardly inclined in a manner whereby a series of segmental blocks may be arranged to fit the conventional lining of a stove, the lower edges of the vertical ribs being notched adjacent the inner faces thereof, the ring having a shoulder portion for receiving the notches in a manner whereby the segments will be firmly held in anchored relation, a flue lining having transversely extending straight walls spanning the curved segments to provide a space between the flue lining and the segments and thereby providing an upwardly extending draft passage, the flue lining being spaced from the drum to provide a vertically extending flue passage between the lining and the drum.

2. In combination with a stove, a grate, a grate supporting ring, a flue supporting means carried by the ring and comprising a plurality of segmental blocks, each segmental block being outwardly curved and having vertically extending inwardly projecting tapering ribs, each block having vertical side edges inwardly inclined in a manner whereby a series of segmental blocks may be arranged to fit the conventional lining of a stove, the lower edges of the vertical ribs being notched adjacent the inner faces thereof, the ring having a shoulder portion for receiving the notches in a manner whereby the segments will be firmly held in anchored relation, a flue formed of a plurality of flue blocks having transversely extending straight walls spanning the curved segments to provide spaces between the flue blocks and the segments and thereby providing upwardly extending draft passages, the flue blocks being spaced from the drum upon oppo-

site sides of the stove to provide vertically extending flue passages between the lining and the drum, said flue blocks being arranged one superimposed upon the other, and said last mentioned blocks having upwardly inclined registering ports extending from the inner toward the outer faces of the blocks.

3. A flue lining supporting segmental block comprising an arc-shaped body having vertically extending ribs, the ribs being inwardly extending with respect to the body, the side edges of the body being inwardly inclined to permit a series of blocks to be arranged in substantially circular formation, and the lower edge of each rib being notched near its inner edge at the bottom thereof to provide a grate-anchoring means.

4. A flue lining block for use in building flue linings for stoves and the like, comprising a fire-resistant body, said body having a straight outer wall and an inclined inner wall, the side edges of the body being inclined from the straight outer wall toward the inclined inner wall, the block having an inclined notch extending upwardly from the bottom of the block from a point inset from the inner wall, the notch being inclined upwardly

toward the outer wall, the block also having a second notch near the top thereof in alignment with the first mentioned notch, the second mentioned notch being inclined upwardly from the face of the inner wall to a point inset from the top of the outer wall in a manner whereby a series of blocks may be set one upon the other to provide upwardly and outwardly inclined flue passages between the abutting upper and lower edges of the respective blocks when set one upon the other.

5. A flue lining comprising a plurality of superimposed blocks, the lower edge of the upper block resting upon the upper edge of the block next below, said blocks having straight transverse faces, said superimposed blocks having registering upwardly and outwardly inclined notches in their abutting upper and lower edges to provide upwardly and outwardly inclined draft passages between the assembled blocks, and the lower edge of said upper block protruding inwardly beyond the upper edge of the block next below to provide a shield and baffle for the draft passages between the blocks.
